UNITED STATES PATENT OFFICE.

PLATO G. EMERY, OF CHICAGO, ILLINOIS.

WINDOW-SHADE.

SPECIFICATION forming part of Letters Patent No. 727,560, dated May 5, 1903.

Original application filed August 20, 1900. Serial No. 27,400. Divided and this application filed August 19, 1901. Serial No. 72,601. (No model.)

To all whom it may concern:

Be it known that I, PLATO G. EMERY, a citizen of the United States, residing at Chicago, in the county of Cook and State of Illinois, have invented certain new and useful Improvements in Window-Shades, of which the following is a specification.

This invention relates to improvements in window-shades of that type which comprise a curtain wound upon a spring-roller and provided with a shade-stick having devices at its ends arranged to travel in grooves in the window-frame and frictionally engage with the frame to hold the curtain against the tension of the spring.

One of the primary objects of the invention is to provide for releasing one or both of the guiding devices at the ends of the shade-stick, so that they can be readily and easily withdrawn from their grooves and the shade disengaged from the window-frame for cleaning and other purposes.

Another important object of the invention is to provide means for adjusting the guiding devices to operate in the grooves of the window-frame yieldingly with sufficient friction and without binding and at the same time provide for quickly withdrawing the guiding devices from the grooves, and another object of the invention is to provide stops at the ends of the stick to prevent complete tilting thereof and at the same time permit a yielding adjustment of the guiding devices to allow for slight variations in the width of the window-frame.

The invention has other objects in view, which will appear hereinafter in the detailed description, reference being had to the accompanying drawings, in which—

Figure 1 illustrates a window-frame provided with a shade embodying my invention. Fig. 2 is a view partly in section, showing an adjustable stop device at one end and a releasing device at the other end of the shade-stick. Figs. 3, 4, and 5 are views partly in section, showing different forms of the invention in which the releasing device is combined with the adjustable stop device. Fig. 6 is a detailed view of the adjusting-sleeve. Fig. 7 is a detailed view of a supplemental guiding-sleeve to prevent the head of the han-

dle from binding against the tubular shade-stick. Fig. 8 is a detailed view of one handle. Fig. 9 is a detailed view of the disengaging-sleeve. Fig. 10 shows the sleeve 38 constructed for use as an adjusting device and also as a releasing device. Fig. 11 shows one end of the torsion-spring 17 attached to the main part of the stick adjacent to the sleeve and the other end connected with the sleeve 69 itself.

The invention consists, essentially, of shade-holding means comprising endwise-adjustable stop devices for holding the guide-shoes in the grooves of the window-frame and means for permitting one or both of these guide-shoes to be retracted for the purpose of withdrawing the guide-shoes from engagement with the frame and out of the grooves. In Fig. 2 of the drawings I have shown a shade-stick provided with an adjustable stop at one end and with a spring-actuated releasing device at the other end, which normally acts as a stop for the guide-shoe, and in Figs. 3 and 4 I have shown an adjustable stop combined with the releasing device at one end of the stick, and in Fig. 5 I have shown the adjustable stop device constructed like the releasing device shown in Fig. 2, except that it has a screw-threaded instead of a spring adjustment. It will be understood at the outset, therefore, that the adjustable stop device and the releasing device may be used independently of each other or together, or they can be combined in one device.

I do not claim, broadly, herein a yielding stop device, as this is claimed in my Patent No. 716,832, granted December 23, 1902; nor do I claim, broadly, herein a friction-foot having a movement independent of the guide-shoe, as this is claimed in a concurrent application filed August 19, 1901, Serial No. 72,602.

Referring to the drawings, in which like numerals of reference denote corresponding parts in the several figures, 10 designates the curtain of my improved window-shade, which is attached to the spring-roller 11 and provided at its lower end with a tubular shade-stick 12, carrying guiding devices 13 at its ends, which are arranged to travel in the vertical guide-grooves 12' in the window-frame.

In the preferred construction of my pres-

ent invention, as illustrated in Fig. 2, I employ a shade stick provided with a releasing device at one end, consisting of a sleeve 14, forming a continuation of the stick and having oppositely-arranged notches or recesses 15 at its outer end of sufficient width to receive the guide-shoe 16 when alined therewith. The sleeve is normally held so that the notches or recesses will be in a plane substantially transverse to the guide-shoe by means of a torsion-spring 17, which has one of its ends set in the guide-shoe, as shown at 18, and its other end passed through a slot 19 in the flange 20 on the end of the sleeve, Fig. 9. The torsion-spring may be otherwise arranged to hold the sleeve in substantially the position shown in Fig. 2—as, for instance, one end 17' thereof could be attached to the main part of the stick adjacent to the sleeve 20 and the other end 17" could be attached to the sleeve itself, as shown in Fig. 11. It will thus be observed that the sleeve is normally held with its notches or recesses out of alinement with the guide-shoe; but when it is desired to move the guide-shoe longitudinally with relation to the stick for the purpose of withdrawing the guide-shoe from its groove the sleeve is turned against the tension of its spring until the notches or recesses are in alinement with the guide-shoe, so that the latter may enter said notches or recesses, which should be of sufficient depth to permit the guide-shoe to be withdrawn from the groove.

The guiding devices carried on the ends of the shade-stick may be of any desired construction, and I do not restrict myself to the particular form illustrated, which consists of an elongated guide-shoe 16, provided with rollers 21 at its ends and having a centrally-disposed spring-pressed friction-foot 22. The guide-shoe is preferably provided with a hollow shank 23, which is arranged within the end of the shade-stick, and the friction-foot 45 is also provided with a hollow shank 24, through the end of which passes a rod 25, which extends approximately to the middle of the shade-stick and carries the pinch-handle 26, which projects through a slot 27 in the stick. The handle 26, Fig. 8, is provided with a round head 28 and a neck 29, and the slot 27 is of sufficient width to permit the neck of the handle to slide freely therein. The head of the handle is inserted in the slot and then turned at right angles into operative position, and it is provided with a screw-threaded opening 30 to receive the threaded end of the rod 25, the head 31 of said rod having a bearing against a shoulder 32 60 within the bore of the shank of the friction-foot. To prevent the head of the handle from binding in the shade-stick and to facilitate the movement thereof, I provide a sleeve 33, Fig. 7, which is arranged on the end of the rod 25 and over the head of the handle and provided with a slot 34 in its side to receive the neck of the handle and having an open-

ing 35 in its inner end to receive the end of the rod. A spring 36 is arranged on the rod between the shank of the friction-foot and a stop 37, fixed within the shade-stick and provided with a central opening, through which the rod 25 passes. This spring normally presses the friction-foot outward into frictional engagement with the back wall of the 75 guide-groove in the window-frame, and as the guiding devices at the ends of the shade-stick are preferably constructed alike it will be readily understood that when the handles 26 are pressed toward each other or pinched the 80 friction-feet will be withdrawn against the tension of their springs out of engagement with the back wall of the grooves, so that the shade may be raised or lowered, but without being removed from the grooves or affecting 85 the guide-shoes.

In Fig. 2 I have shown an adjustment for the shade-stick in the form of a sleeve 38, having a screw-threaded connection at 39 with the end of the shade-stick and forming a continuation thereof. In this construction the sleeve 38 forms a stop device at one end of the stick and the releasing device forms a stop device at the other end, and the spring 17 holds the sleeve 38 yieldingly in engagement 95 with the guide-shoe.

In Figs. 3, 4, and 5 I have shown a releasing device combined with the adjustable stop device and a spring 40 arranged between the stop 37 and the end of the shank 23 of the 100 guide-shoe. In the construction of Fig. 3 the sleeve 38 is arranged loosely on the shank 23 of the guide-shoe and provided with a screw-threaded connection at 39 with the end of the shade-stick, and it also has an annular finger-piece 41 at its outer end to facilitate its adjustment. This sleeve is normally adjusted out of contact with the guide-shoe; but the latter abuts against the sleeve when the handles are pinched and is prevented thereby from being accidentally withdrawn from the groove. In the construction of Fig. 4 the shank 23 of the guide-shoe is screw-threaded and a nut 42 is arranged thereon between the guide-shoe and an end of the shade-stick, 115 by means of which the adjustment is effected. In Fig. 5 I have shown a spring 40 for throwing the guide-shoe into normal operative position and an adjusting device consisting of a sleeve 43, substantially similar to the sleeve 120 14, shown in Fig. 2, except that it has a screw-threaded connection at 44 with the end of the shade-stick instead of the torsion-spring. In this construction the releasing device is operated in precisely the same manner as in the construction of Fig. 2, and it also performs its function as an adjustable stop device substantially in every respect similar to the adjustable stop device provided by the sleeve 38 in Figs. 2 and 3. The sleeve 130 38 in Figs. 2 and 3 can be made to correspond to the sleeve 43 in Fig. 5 by simply providing it with the notches or recesses 15, as shown in Fig. 10, and when so constructed this sleeve

at one end of the shade-stick can be employed as an adjusting device and also as a releasing device.

My invention provides shade-holding means of novel construction which are adapted to hold the curtain against the tension of the spring-roller and at the same time permit of its being readily adjusted without liability of the guiding devices becoming withdrawn from the grooves, which is of especial importance in this art, as the shades are manipulated more or less carelessly, and it is desirable to maintain the guiding devices in their proper operative arrangement in the grooves at all times. Whenever it is desired to clean the curtain or to remove the guiding devices from the groove and release the curtain from its guided arrangement, the guiding devices are allowed to enter the notches or recesses at the end of the stick, which enables the stick to be tilted sufficiently to withdraw both of the guiding devices from the grooves, and in this connection the invention consists, broadly, of a shade-stick provided with notches or recesses at its end and a guiding device carried by the shade-stick and adapted to enter said notches or recesses.

The notch or recess 15 in the sleeve 14 will be referred to in the claims simply as a "notch," and it will be understood as comprehending any construction of the sleeve which will permit the withdrawal of the guiding devices in the manner contemplated by the invention.

Having thus fully described my invention, what I claim, and desire to secure by Letters Patent, is—

1. The combination with a shade-stick, of elongated guiding devices at the ends of the stick to travel in the grooves of a frame and movable longitudinally of the stick, said guiding devices being extended above and below the stick to prevent the stick from tilting out of the grooves while in operative position, and a stop device constituting one end of the stick and adjustable longitudinally thereof to lengthen the stick so that the ends of the stick will permit a limited inward movement of the guiding devices but at the same time prevent them from tilting out of the grooves.

2. The combination with a shade-stick, of spring-pressed guiding devices at the ends of the stick, elongated transversely to the axis of the stick, and an adjustable stop carried by the stick adjacent to one of the guiding devices and arranged to prevent complete tilting of the shade-stick but permitting a yielding adjustment of the guiding devices.

3. The combination with a shade-stick, of guiding devices at the ends of the stick elongated transversely to the axis of the stick to travel in the grooves of a frame, a stop device operating in connection with the stick to prevent the guiding devices from tilting out of the grooves, and a spring for permitting a limited yielding movement of the guiding devices longitudinally of the stick.

4. The combination with a shade-stick, of guiding devices at the ends of the stick elongated transversely to the axis of the stick to travel in the grooves of a frame, stops at the ends of the stick to engage the guiding devices and prevent them from tilting out of the grooves, one of said stops being capable of adjustment to permit removal of the guiding devices from the grooves, and a spring for permitting a limited yielding movement of the guiding devices longitudinally of the stick.

5. A shade-stick having notches at its end, and a guiding device carried by the shade-stick in the groove of a frame, said notches and guiding device designed to be normally arranged out of alinement and said guiding device being adapted to enter the notches when alined therewith.

6. A shade-stick having notches at its end, and a spring-pressed guiding device designed to be normally arranged out of alinement with the notches, and adapted to enter the same when the notches are located in alinement with the guiding device.

7. A shade-stick carrying a guiding device arranged to travel in the groove of a frame, said stick including a sleeve at the end thereof provided with notches, said notches and guiding device designed to be normally arranged out of alinement and said guiding device being adapted to enter the notches when alined therewith.

8. A shade-stick having a notched sleeve at its end, a guiding device adapted to enter the notches in the sleeve, and means for holding the sleeve with its notches out of alinement with the guiding device.

9. A shade-stick having a notched sleeve at its end, a guiding device adapted to enter the notches in the sleeve, and a spring yieldingly holding the sleeve with its notches out of alinement with the guiding device.

10. A shade-stick carrying a guiding device arranged to travel in the groove of a frame, and a rotatably-movable sleeve at the end of the stick provided with notches to receive the guiding device when the latter is withdrawn from the groove.

11. The combination with a hollow shade-stick, of an elongated guide-shoe having its shank arranged in the end of the shade-stick, and an adjustable device at the end of the shade-stick to form a stop for the guide-shoe and normally prevent complete tilting of the shade-stick.

12. The combination of a shade-stick, a guide-shoe carried by the stick, an adjustable stop for said guide-shoe, and means for yieldingly holding said stop in constant contact with the guide-shoe.

13. The combination with a hollow shade stick, of an elongated spring-pressed guide-shoe having its shank arranged within the end of the shade-stick, a friction-foot operating within the guide-shoe and preventing the shank of the guide-shoe from slipping out of

the shade-stick, and an adjustable device arranged at the end of the shade-stick and forming a part thereof and constituting a stop for the guide-shoe to normally prevent complete 5 tilting of the shade-stick.

14. The combination with a hollow shade-stick, of a friction device, a rod connected to said friction device and arranged within the shade-stick, a handle having a head attached 10 to the inner end of said rod, said handle projecting through a slot in the shade-stick and a guiding-sleeve arranged over the head of the handle at the end of the rod.

15. The combination with a shade-stick, of

elongated guiding devices carried by the stick 15 to travel in the grooves of a frame, stops at the ends of the stick to engage the guiding devices and prevent the guiding devices from tilting out of the grooves, one of the stops being provided with notches and adapted to be 20 adjusted rotatably in position to receive the adjacent guiding device, and a spring for holding the guiding devices yieldingly in engagement with the frame.
